DESIGN FOR A SELF-PROPELLED SURF- BOARD

Bert Lee, Sacramento, Calif.

Application December 5, 1941, Serial No. 104,493

Term of patent 3½ years

To all whom it may concern:

Be it known that I, Bert Lee, a citizen of the United States, residing at Sacramento, in the county of Sacramento and State of California, have invented a new, original, and ornamental Design for Self-Propelled Surfboard, of which the following is a specification, reference being had to the accompanying drawing, forming a part thereof.

Figure 1 is a top plan view of a self-propelled surfboard, showing my new design;

Figure 2 is a side elevational view of the same; and

Figure 3 is a transverse section on line 3—3 of Fig. 1.

I claim:

The ornamental design for a self-propelled surfboard, as shown.

BERT LEE.
